CLAIM

The ornamental design for a squeezable container for liquid and lotion dispensing, as shown and described.

DESCRIPTION

FIG. 1 illustrates a front view of a squeezable container for liquid and lotion dispensing showing my new and ornamental design;

FIG. 2 illustrates a bottom view thereof;

FIG. 3 illustrates a front view, partly in section, showing a cover portion attached thereto; and,

FIG. 4 illustrates a perspective exploded view showing all of the components thereof.
